UNITED STATES PATENT OFFICE

131,413

DESIGN FOR AN ELECTRIC VAPORIZER

Joseph Robinson, New York, N. Y.

Application March 12, 1940, Serial No. 90,845

Term of patent 14 years

To all whom it may concern:

Be it known that I, Joseph Robinson, a citizen of the United States, residing at New York, in the county of New York and State of New York, have invented a new, original, and ornamental Design for an Electric Vaporizer, of which the following is a specification, reference being had to the accompanying drawing, forming a part thereof.

The figure is a side elevational view of an electric vaporizer showing my new design, which is substantially round in cross-section throughout its length.

I claim:

The ornamental design for an electric vaporizer, substantially as shown and described.

JOSEPH ROBINSON.
